(57) **CLAIM**

The ornamental design for a memory card reader, as shown and described.

DESCRIPTION

FIG. 1 is a bottom, front and right side perspective view of a memory card reader showing my new design;

FIG. 2 is a top, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1; and,

FIG. 10 is an enlarged view of portion 10 in FIG. 3.

The evenly dashed broken lines illustrate portions of the memory card reader. The unevenly dashed broken lines define the boundaries of enlarged views and form no part of the claimed design. None of broken lines form part of the claimed design.
